BOTTLE VENDING MACHINE

Clare E. Hodgman, Mamaroneck, N.Y., assignor to The Coca-Cola Company, Atlanta, Ga., a corporation of Delaware

Filed Mar. 2, 1960, Ser. No. 59,586

Term of patent 14 years

(Cl. D52—3)

The opposite side of the bottle vending machine is substantially the same in appearance as the side shown and the rear is unadorned.

The drawing is lined to indicate contrast in color.

The essential features of my new design are shown in solid lines.

I claim:

The ornamental design for a bottle vending machine, as shown and described.
